Henry D. James,
BY
Wesley S. Barr
ATTORNEY

UNITED STATES PATENT OFFICE

HENRY D. JAMES, OF EDGEWOOD, PENNSYLVANIA, ASSIGNOR TO WESTINGHOUSE ELECTRIC & MANUFACTURING COMPANY, A CORPORATION OF PENNSYLVANIA

SWITCH

Application filed November 29, 1921. Serial No. 518,519.

My invention relates to switches and its has particular relation to switches for interrupting circuits that are traversed by relatively large currents.

5 One object of my invention is to provide a switch having all its parts so arranged that ready access thereto may be effected.

Another object of my invention is to provide means for readily removing an arc box from a switch upon which it is mounted.

10 A further object of my invention is to provide an improved blow-out device for extinguishing the arc that is established between the contact members of a switch when 15 the circuit comprising the switch is interrupted.

Briefly speaking, my invention consists in providing a slidably-mounted core member within the blow-out coil of a switch, securely 20 mounting a plurality of pole-pieces upon an arc box and so mounting the arc box upon the switch that the pole-pieces will engage the core member when the arc box occupies its operative position.

25 For a better understanding of my invention, reference may be made to the accompanying drawing, wherein—

Figure 1 is a view, partly in side elevation and partly in section, of a switching device embodying my invention; and

30 Fig. 2 is a bottom plan view of a portion of an arc box that is illustrated in Fig. 1 of the drawing.

Referring particularly to Fig. 1 of the 35 drawing, a switch 1 comprises a plurality of contact members 2 and 3, a plurality of arc horns 4 and 5, a blow-out coil 6 and an arc box 7. The blow-out coil 6, stationary arc horn 4 and stationary contact member 2 are 40 securely mounted upon a plurality of vertical mounting bars 8 which are covered by suitable insulating material.

The stationary arc horn 5 is secured to the vertical mounting bars 8 by means of a 45 plurality of bolts 9 and a relatively flat mold-

ing or clamping member 11. The movable contact member 3 is pivotally mounted upon a lever 12 by means of a pin 13 and is actuated thereby. The contact member 3 is 50 yieldingly maintained in predetermined angular relation to the lever 12 by means of a resilient member (not illustrated). The lever 12 is pivotally mounted upon a stationary member 14 by means of a pin 15. The lever 12 is actuated by a connecting lever 16, 55 to which it is mechanically connected by a pin 16a (indicated by broken lines).

The connecting lever 16 is mechanically connected to a piston rod 17 by means of a pin 18. A piston 46 is mounted within a cylinder 19 and is secured to the piston rod 17. The piston is actuated by fluid pressure 60 which is governed by an electromagnetic valve device 21. The piston rod 17 is biased to its lower position, which is that illustrated in the drawing, by means of a resilient member or spring mounted within the cylinder 19. An auxiliary contact device 20, constituting a portion of the switch 1, is governed by the movement of the piston rod 17.

The arc box 7 has two vertical side walls 23 and 24, on each of which is secured a plurality of pole-pieces 25, 26 and 27. Each of the side walls 23 and 24 comprises a plurality of asbestos boards 23a and 24a, respectively. Pole-pieces 27 are spaced sufficiently apart to clear the coil 6 and to frictionally engage the core member 28 that is slidably mounted therein. The magnetizable pole-pieces 26 serve as spacing members between the pole-pieces 25 and 27.

70 When the arc box 7 occupies its operative position, the pole-pieces 25 are in side-by-side relation with the contact members 2 and 3 and are separated therefrom by the asbestos 75 boards 23a and 24a, as is illustrated by Figs. 1 and 2 of the drawing.

A horizontal cover member 29, made of some suitable insulating material, is provided at the top of the switch 1 and is secured 80

to the vertical mounting bars 8. A plurality of insulating blocks 31 are provided for preventing the arc that may be established between the contact members 2 and 3 and the 5 arc horns 4 and 5 from passing around the upper end of the stationary arc horn 4 to the blow-out coil 6.

The cover member 29 is provided with a plurality of clip angle members 32 (preferably two), which are rigidly secured thereto. 10 The arc box 7 is provided with a corresponding number of clip angle members 33 which are secured thereto. A plurality of bolts 34 are employed to mechanically connect the clip 15 angle members 32 and 33 together, thus securing arc box 7 to the upper insulating member 29.

The lower portion of the arc box 7 is provided with a plurality of insulating barriers 20 35 and 36. A pin 37 is secured, by means of a bracket member 38 and a plurality of bolts 39, to the side members 23a and 24a of the arc box 7. The bolt 37 rests in a socket that is provided in the cylinder 19. The bracket 25 member, or casting, 38 is provided with relatively flat side and bottom portions or lugs 40 and 41, respectively, to limit the rotatable movement of the arc box 7 about the pin 37.

The arc box 7 may be removed from the 30 switch by first removing the bolts 34 from the clip angle members 32 and then swinging the arc box in a counter-clockwise direction about the pin 37 until the arc box can be lifted upwardly from the socket 40a.

35 When the arc box 7 has been removed, the pole-pieces 25, 26 and 27 are simultaneously removed, thereby permitting access to the blow-out coil 6, arc horns 4 and 5, and contact members 2 and 3. The arc box 7 may be 40 placed in its operative position by reversing the operation that is required for its removal from the switch 1.

The operation of the switch is as follows:—

When the electromagnetic device 21 is energized, fluid pressure from a port 42 passes 45 a valve member—not illustrated—that is governed by the device 21. Fluid pressure actuates the piston within the cylinder 19, thereby raising the rod 17, connecting lever 16, 50 lever 12 and, hence, contact member 3, until it is brought into contact with the stationary contact member 2.

When the contact members 2 and 3 are in engagement, a circuit is established from a 55 stationary contact terminal 43 through the blow-out coil 6, contact members 2 and 3, and flexible conductor 44 to stationary terminal 45. When the magnetic device 21 is de-energized, pressure is removed from the piston 60 within the cylinder 19, and a resilient member (not illustrated) also within the cylinder 19, actuates the piston rod 17 downwardly, thereby separating the contact member 3 from the contact member 2, in accordance 65 with familiar principles.

The arc established between the contact members 2 and 3 is forced outwardly, by the magnetic flux from the blow-out device, along the arc horns 4 and 5, which are electrically connected to the contact members 2 and 3, respectively. The magnetic circuit constituting a portion of the blow-out device comprises the core member 28 and the pole pieces 25, 26 and 27, which become magnetized, when the coil 6 is energized.

70 From the above description, it is apparent that I have provided an arc box having a plurality of pole-pieces secured thereto that may readily be removed to permit access to the contact members and blow-out device of the switch.

75 While I have shown a switch constructed in accordance with my invention in its preferred form, it is apparent that minor modifications may be made in the arrangement of the parts of the switch without departing from the spirit of my invention. I desire, therefore, to be limited only by the scope of the appended claims.

80 I claim as my invention:—

1. In a switching device, the combination with a plurality of contact members and a blow-out coil, of an arc box, a plurality of pole-pieces secured to said box and a pivotal support for said box, said support being relatively removed from said members and said coil and adapted to permit the removal of said box from said device upon said box occupying a predetermined position.

85 2. In a switching device, in combination, 100 a frame, a socket carried by the frame, an arc chute, a complementary hinge member provided on the chute for engaging in the socket to removably and pivotally mount the chute, means provided on the frame for receiving the arc chute and means for locking the arc chute in engagement with said receiving members.

90 3. In a switching device, in combination, 105 a frame, a socket carried by the frame, an arc chute adapted for mounting on the frame, a complementary hinge member for mounting on the chute for engaging in the socket to removably and pivotally mount the chute, arc shields carried by the frame and disposed to receive the upper part of the arc chute and means for locking the arc chute 110 in position.

95 4. In a switching device, in combination, 115 a frame, switching members mounted on the frame, an arc chute for enclosing said switching members, complementary hinge members mounted on the frame and chute for removably and pivotally mounting the latter, an arc shield shaped to receive the upper side 120 of the arc chute and means carried by the arc shield for locking the arc chute in position.

125 5. In a switching device, in combination, a frame, a plurality of switching members car- 130

ried by the frame, an arc chute for enclosing the switching members, complementary hinge members provided on the frame and chute for removably and pivotally mounting the latter, an arc shield carried by the frame and disposed above the switching members, said arc shield and chute being provided with interengaging edges to provide an arc channel for controlling the direction of travel of an arc, and means for locking the arc shield and arc chute in engagement.

In testimony whereof, I have hereunto subscribed my name this 18th day of November, 1921.

15

HENRY D. JAMES.
